SAND BLASTING MACHINE

Murray T. Swisher, Clairton, Pa.

Application April 6, 1940, Serial No. 328,301

3 Claims. (Cl. 51—9)

This invention relates to sand blasting machines and is directed to more particularly an apparatus wherein the abrasive material is projected and directed against the work by means of an impeller wheel.

One of the objects of the present invention is to provide a centrifugal abrading apparatus in which the impeller wheel, when rotated at high speed, produces a strong current of air, thereby greatly increasing the force at which the abrasive material deposited on said impeller wheel is projected against the work.

Another object of the invention is to provide a centrifugal abrading machine with an impeller wheel assembly in which the location of the feeding spout through which the abrasive material is fed to the impeller wheel may be varied.

Still another object of the invention is to provide an abrading apparatus in which the amount of abrading material fed to the impeller wheel may be controlled without changing any parts.

Yet another object of the invention is to provide a centrifugal abrading machine which is adapted to be used for producing decorative designs, printing, etc. on glass or metal by removing the luster or smooth surfaces therefrom.

Another object of the invention is to provide a centrifugal abrading machine in which articles with large surfaces may be evenly sand blasted, yet the stream of abrading material projected and directed against the articles does not necessarily strike the whole surface which is to be sand blasted at one time.

A still further object of the invention is to provide a centrifugal abrading apparatus in which the work support may be raised or lowered and turned for a predetermined portion of a circle at every "up" movement of the work support.

Another object of the invention is to provide a centrifugal abrading machine in which the work support may be continuously rotated for producing sand blasted designs, lettering, etc. on cylindrical articles.

Further objects of the invention are to provide an apparatus of the class set forth which is simple in its construction and arrangements, efficient in its use, operable by inexperienced persons and inexpensive to manufacture.

To the accomplishment of these and such other objects as may hereafter appear the invention consists of the novel construction, combination and arrangement of parts herein specifically described and illustrated in the accompanying drawings wherein is shown an embodiment of

the invention, but it is to be understood that changes, variations and modifications may be resorted to which come within the scope of the claims hereunto appended.

5 In the drawings wherein like numerals of reference designate corresponding parts throughout the several views,

Figure 1 is a side elevation of the device embodying the invention, partly in cross section and the sidewalls eliminated.

Figure 2 is a front elevation of Figure 1 taken substantially on line 2—2 of Figure 1.

Figure 3 is a top view of Figures 1 and 2.

Figure 4 is a sectional view taken on line 4—4 of Figure 1.

10 Figure 5 is a fragmentary view of the cooperating parts by means of which the work board upon which the articles to be sand blasted are mounted is intermittently rotated, in this case for a one quarter turn.

Figure 6 is a view similar to Figure 5 showing the pawl in contact with one of the studs of the rotatable stud wheel secured to the work board.

15 Figure 7 is an enlarged top view of the hollow disc which is movably mounted on the upper wall of the impeller wheel housing serving to supply air to the impeller wheel and also serving to deposit abrading material on the impeller wheel in various radial positions thereby varying the angular spray force of the abrading material.

20 Figure 8 is a sectional detail side view on line 8—8 of Figure 7 showing the features outlined above and, in addition, indicating by arrows, the travel of the air stream created by the impeller wheel.

Figure 9 is a fragmentary outline side view of Figure 8.

25 Figure 10 is a fragmentary top view of the impeller wheel.

30 Figure 11 is a fragmentary perspective view of the impeller wheel including one of the blades therefor.

Figure 12 is a cross sectional side view of a modified form of impeller wheel assembly showing a solid disc or block provided with a large central air intake opening.

35 Figure 13 is an enlarged cross section of one of the suction cups as used on the work board for holding flat articles while sand blasting.

40 Figure 14 is a perspective view of the sand bin as used in the invention having part of the side walls broken away to show the interior thereof.

45 Figure 15 is a top view of Figure 14.

50 Figure 16 represents a fragmentary sectional

view on the line 16—16 of Figure 15, the upper portion of the sand bin being shown broken away.

Figure 17 is an enlarged perspective view of the handle bar of the selector disc including the locking mechanism for the latter.

Figure 18 illustrates a side view of the complete apparatus as shown in Figure 1 with parts of the walls broken away and as used to sand blast round articles, such as glasses, etc.

Figure 19 is a top view of Figure 18, the impeller wheel cabinet being broken away.

Figure 20 is a fragmentary front elevation sectioned on line 20—20 of Figure 19.

Referring now to Figures 1 2 and 3 inclusive, the apparatus shown consists in general of two distinctive cabinets, the impeller wheel cabinet 25 and the work cabinet 26.

Cabinet 25 contains an impeller wheel 27 mounted for rotation on a vertical shaft 28 which is rotatably mounted in ball bearings 29 and 30 supported on horizontally disposed cross strips 31 and 32 respectively, as shown.

Said vertical shaft 28 is shown driven by means of an endless belt 33 trained over a set of pulleys 34 and the power being supplied by an electric motor 35.

The lower portion of said cabinet 25 is provided with an impeller housing 36, preferably of rectangular contour, having side walls 37 and 38, a rear wall 39, an inclined bottom 40 and a horizontal top wall 41. The front portion 42 of said housing 36 extends slightly beyond the cabinet 25 and terminates into a rectangular flanged end 43.

Said top wall 41 is provided with a bore 44 and a counterbore 45 adapted to receive an annular block 46 which is shown on an enlarged scale in Figure 12 of the drawings.

The block 46 has an annular flanged extension 47 which rests in said counterbore 45 of top wall 41 and is held in sliding contact by flat springs 48 in a manner as shown in Figure 7. The large central aperture 49 in block 46 serves to accommodate the impeller shaft 28 and to permit air to enter the impeller wheel 27.

Block 46 is also provided with an outwardly extending operating handle 50 secured to the top face 51 thereof by which the block 46 may be horizontally and circumferentially shifted when it is desired to change the circumferential location of the sand feeding aperture 52 in which is inserted the free end of a flexible tube 53 leading from the bottom of the sand box 54 (Figures 1 and 16). By shifting said block 46 as above described the location of the sand feeding outlet 52 through which the abrading material is discharged by gravity to the impeller wheel 27 may be readily changed, thereby causing an increase or decrease of the angular spray of the abrasive against the work to be sand blasted.

The circumferential movement of said block 46 may be checked by stop pins 55 or 56 as shown, or otherwise.

In order to obtain the proper suction effect of the impeller wheel 27 the top portion of the latter should be, when assembled, in close parallel alignment with the lower face 57 of block 46 as shown in Figure 12.

Block 58 (Figures 7 and 8) shows a modified construction of the block 46 heretofore mentioned and the former comprises a top disc 59 provided with an annular flange 60, and a bottom disc 61, both of which are securely held apart by spacers 62 so as to form a hollow structure.

The outer peripheries of said discs 59 and 61 are in alignment and are covered with a screen 63.

Top disc 59 is provided with a central bore 64 of sufficient size to clear the impeller shaft 28 while the bottom disc 61 has a central bore 64a of larger dimension. In this construction, the block 58 serves as an air intake means which supplies the impeller wheel 27. The air for the impeller wheel 27 enters through the screen 63 secured around the periphery of the hollow block 58 and leaves through bore 64a of the bottom disc 61.

The flexible tube 53 from sand box 54 is inserted in coincident openings 65 and 66 having a sleeve 67 secured therebetween. Otherwise the construction and operation of block 58 is same as for block 46 previously described.

The impeller wheel 27 consists of an annular base-plate 68 having a plurality of blades 69 (Figure 11) secured thereon and spaced and placed as shown in Figure 10 of the drawings. Said blades 69 are preferably formed of sheet material of substantially triangular outline having the edge 70 bent upwardly and inwardly as shown and indicated by the numeral 71 in Figure 11.

Abrasive material is supplied to the impeller wheel 27 from a sand box 54 which is provided with an inclined bottom wall 72 which merges into the horizontal bottom 73 as best shown in Figures 14 to 16 inclusive. This horizontal bottom 73 is provided with an out-passage 74 for the sand having a flexible tube 53 inserted and secured therein, the free end of which terminates in the feeding aperture 52 of block 46, as heretofore described.

The abrasive material as herein used includes such as finely divided dry sand or artificial abrasives such as metallic grit or other artificial cutting material and is adapted to gravitate from the sand-box 54 to block 46 and then be deposited, also by gravity upon the impeller wheel 27.

It is often required to project a small or a large quantity of abrasive without changing the speed of the impeller wheel 27, this is accomplished by providing the out-passage 74 of sand box bottom 73 with a manually operated selecting disc element 75 which consists of a circular, substantially flat disc 76 provided, in this case with four differently sized openings 77 on a common radius and equally spaced. When assembled, this disc 76 is so arranged that by turning the rod 78 one of the openings 77 of disc 76 will register with the out-passage 74 which, of course, must be larger than any of the openings 77 of disc 76. Rod 78 is centrally secured to the latter and the stub end 79 is rotatably inserted in aperture 80 of sand box bottom 73 and held in position by a nut 81 or otherwise.

The upper end 82 of said rod 78 extends upwardly to a point near the upper edge 83 of sand box 54 and is rotatably retained in a star-like element 84 which is fastened to the sand box wall by means of an angle piece 85.

Referring now to Figure 17 there is shown a perspective view of the selecting device by means of which the desired size of opening 77 of disc 76 will register with the out-passage 74 of sand box bottom 73 without requiring the sand box to be emptied. The upper end 86 of rod 78 is preferably flattened and bent over to form a handle 87 by means of which the selector disc 76 may be turned. Slightly below said handle 87 is pivotally mounted the locking pawl 88, the lower end of which terminates into a strip extension 89 which

is adapted to engage one of the four slots 90 of star-like element 84. Each of said slots 90 correspond with one of the openings 71 of disc 76 and the star element 84 may be marked, as shown, to identify the size of opening 71 registering with out-passage 74.

The upper portion of said locking pawl 88 is bent over as shown, to form a handle 91 so as to enable the operator to grip the rod handle 87 and the pawl handle 91 at the same time. A leaf spring 92 is secured to the underside of said pawl handle 91 and the free end of the spring rests on the rod handle 87.

In operating the selecting disc element 75 the workman grasps with one hand both handles 87 and 91 thereby removing the extension 89 (see dot and dash lines in Figure 17) out of engagement of one of the slots 90 of the star element 84. By turning handles 87 and 91 to the desired slot 90 and releasing the spring tensioned handle 91 the extension 89 will enter the slot and thereby prevent rotation of the disc element 75.

The work cabinet 26 as shown in Figures 1, 3 and 4 serves as a work chamber in which the articles to be decorated are subjected to the sand blast.

The same comprises a rectangular box having side walls 94 and 95, a rear wall 96, a front wall 97 and an inclined bottom 98. The spent sand may be removed through the opening 99 located in the lowermost end of front wall 97 by dropping the hinged door 100. The open upper end of cabinet 26 through which the workman may observe the progress of the work or insert the work is provided with a hinged cover 101.

The rear wall 96 of cabinet 26 is provided with a rectangular opening 102 which substantially corresponds to the rectangular flanged end 43 of the impeller wheel cabinet 25. A gasket 103 may be inserted between said rear wall 96 and said flanged end 43 before joining them together to prevent dust to escape around the seam.

Said cabinet 26 is provided in each corner, facing the front, with a pair of spaced apart upright rails 104 and 105 in which a work-board support 106 is slidingly inserted. Said support 106 may be raised or lowered by means of a crank handle 107 directly attached to one end of a stub shaft 108 which is rotatably supported in the upper front wall 97, while the other end of said stub shaft 108 is secured to a grooved pulley 109 to which one end of a cable or rope 110 is secured while the other end of said rope is fastened to the work board support 106 in a manner as shown in Figures 1, 3 and 4, or otherwise.

As previously mentioned, the herewith described apparatus is especially adapted to sand blast flat articles of glass, metal or other suitable materials of a size equalling the area of the work board 111, or if desired several smaller flat objects of a total area of the work board 111 may be sand blasted at one time, but it should be noted that only a substantially narrow band of abrasive is expelled by centrifugal force from the impeller wheel 27 and strikes the articles to be sand blasted. It is therefore one of the main features of the present invention to, not only move the work board 111 on which the articles to be sand blasted are secured in a vertical direction but also impart an intermittent circular motion to the same.

It is for that reason that said work board 111 is mounted for intermittent circular motion upon the work board support 106 and this is accom-

plished by providing a pin connection 112 which is rotatably supported in the work board support 106.

This pin connection 112 has securely mounted on the end 113 facing the impeller wheel 27 the work board 111 and on the opposite end 114 a pin wheel 115, in other words, the workboard 111 is mounted on one side of the work board support 106 and the pin wheel 115 on the other side of the same.

A pin wheel pawl 116 which cooperates with pin wheel 115 is mounted on the inner face of front wall 97 in close proximity of the pulley 109.

In operation, the workman slowly turns the crank-handle 107, thereby raising the workboard support 106 including of course the workboard 111 and the pin wheel 115 until the lowermost edge 117 of said pawl 116 strikes one of the pin wheel pins 118 (Figure 6) thereby causing the pinwheel 115 and the work board 111 to rotate, in this case, since there are four pins 118 on the pin wheel, for a quarter turn, after which the spring tensioned cam lever 119 retains the work board 111 and pin wheel 115 in a position as shown in Figure 5.

It should be observed, that the work board support 106 including the work board 111 when in "up" position will extend outwardly of the work cabinet 26 and in that position flat articles 120 to be sand blasted may be applied and retained in position by suitable rubber suction cups 121, mounted on the work board 111 in a well known manner (Figures 1, 3, 4 and 13).

In order to keep the work board 111 and its support 106 in "up" position, while placing or removing work, the peripheral edge 122 of pulley 109 facing the inner side of front wall 97 is provided with ratchet teeth 123 cooperating with a ratchet pawl 124. The latter may be brought out of engagement of the ratchet teeth from the exterior of the work cabinet 26 by a knob 125, or otherwise (Figures 1 and 4).

The operation of the work board mechanism has been illustrated as manually operated but it is clear that it may be operated from the same motor which spins the impeller wheel.

In general, the operation of the device is as follows:

Assuming that the sand box 54 is filled with abrasive, the electric motor is connected to a supply line and flat articles are held by suction cups 121 on the work board 111, ready to be decorated by sand blasting.

As the electric current is turned on the motor spins the impeller wheel 27 which receives abrasive material from the sand box 54 by gravity through block 46. The abrasive is thrown horizontally and outwardly and against the work to be sand blasted by centrifugal force aided by the airstream and vacuum developed by the blades of the impeller wheel 27. At that stage, the abrasive so discharged against the work would sand blast a narrow strip of the work only and it is for that reason that it is necessary to move the work board up and downwardly and in addition to turn it at every "up" movement for a quarter of a turn.

As the operator slowly turns the crank handle 107 in clockwise direction the work board 111 is raised until one of the four pins 118 of pin wheel 115 strikes the pin wheel pawl 116 thereby imparting a quarter turn to the work board 111 as previously explained.

The operator now slowly turns the crank handle 107 in a counter clockwise direction thereby

lowering the work board until it strikes the bottom, and again the operator raises the work board in a manner as heretofore described. These operations are repeated until the work is completed.

In this manner the articles will be sand blasted in compounded directions which in turn will produce an even and smooth sand blasted finish.

Referring now more particularly to Figures 18, 19 and 20 there is shown an attachment to the above described construction by means of which cylindrical articles may be sand blasted.

In this attachment three pedestals 126, 127 and 128 are mounted in axial alignment on a supporting strap 129, as shown. Pedestal 127 is rigidly mounted on said strap 129 and this pedestal rotatably supports a short shaft 130. The latter extends at both ends of bearing 131 and has annular discs 132 provided with hubs 133 mounted thereon. A rounded soft rubber pad 134 is cemented or otherwise secured to the outer face of disc 132.

Pedestal 126 is slidably mounted on supporting strap 129 having a disc 132 and rubber pad 134 mounted on the inner end of shaft 135, while the opposite end of the latter is provided with a collar 136 which prevents the shaft from sliding out of the bearing 137.

Pedestal 128 is of similar construction as pedestal 126 with the exception that the shaft 138 extends outwardly of the work cabinet 26 and carries a pulley 139 which may be connected by a belt 140 to an electric motor (not shown) or otherwise.

Pedestal 126 and 128 are slidably supported on said strap 129 and may be moved axially by means of a screw connection 141, one end of which extends outwardly of cabinet 26, as shown. Of course, all of said shafts 130, 135 and 138 are in horizontal alignment with the impeller wheel 27 as best shown in Figure 18.

In operation, glasses or other cylindrical objects may be clamped between the soft rubber pads 134 or freed from the same by turning the knob 142 of screw connection 141, but otherwise the operation is identical with the apparatus adapted especially for sand blasting flat articles such as previously described.

In view of the above, it is believed that the various features of the present invention will be clear without further elaboration, and it will be seen that with the apparatus herein described, the several objects of the invention are achieved and other advantageous results are attained.

The invention may be embodied in other specific forms without departing from the spirit or essential characteristics thereof and the present embodiment is therefore to be considered in all respects as illustrative and not restrictive, the scope of the invention being expressed by the appended claims rather than by the foregoing description, and all changes which come within the meaning and range of equivalency of the claims are therefore intended to be embraced therein.

I claim:

1. In an abrading machine, a frame, a housing mounted horizontally in said frame and open at its front end, a shaft rotatably mounted vertically in the frame over said housing with its lower portion entering the housing, an impeller

wheel fixed upon the shaft within the housing, a hollow block surrounding the shaft over said wheel and having spaced upper and lower walls and a peripheral wall of foraminous material for admitting air into the block, the lower wall of the block being formed with an opening about the shaft for delivering air to the center of the impeller wheel, upstanding blades extending substantially radially of the impeller wheel and having side flanges along their upper edges, said blades having their inner ends spaced from each other and spaced from the shaft, a sand box in said frame over said housing having a tube leading from the sand box for delivering sand through the block and onto the impeller wheel, means for rotating said shaft to spin the wheel and discharge sand therefrom through the open end of the housing, a work chamber having an inlet registering with the open end of the housing, and means in the work chamber for supporting an article in position to be acted upon by a sand blast entering the work chamber from said housing.

2. In an abrading machine, a frame, a housing in said frame open at its front end, a shaft rotatably mounted in said frame and entering the housing, an impeller in said housing actuated by said shaft, a sand box mounted in said frame and having an outlet tube for delivering sand to the impeller wheel, a work chamber disposed vertically in front of said frame and having its rear wall secured to the front end of said housing and formed with an inlet registering with the open end of the housing for discharge of a sand blast from the housing into the work chamber, a support shiftable vertically in the work chamber, a work holder carried by the support and rotatable about a horizontal axis, means for shifting the support vertically, and means for imparting partial turns to the work holder in step-by-step movements during vertical movement of the support.

3. In an abrading machine, a frame, a housing mounted horizontally in said frame and open at its front end, an impeller operating in the housing for discharging a sand blast through the open end thereof, a sand box mounted in said frame and having an outlet tube for delivering sand to the impeller, a vertical work chamber having a rear wall secured to the front end of said housing and formed with an inlet opening registering with the open end of the housing, vertical tracks in the work chamber, a support slidable vertically along the tracks, a shaft journaled horizontally through said support, a work holder fixed to the rear end of the shaft, means for securing work to be sand blasted against the rear face of the work holder, a disc fixed to the front end of the shaft, pins extending from said disc in spaced relation to each other circumferentially thereof, a pawl yieldably held in position to engage said pins and hold the shaft and the work holder against turning, means for shifting the support upwardly and then downwardly along the tracks for reciprocating movement across a sand blast, and an abutment for engaging a pin as the support approaches one end of its reciprocating movement and imparting turning adjustment to the shaft and the work holder.

MURRAY T. SWISHER.
